APPARATUS FOR MAKING INFLAMMABLE GAS

William G. Holzschuh, Rochester, N. Y.

Application May 12, 1931. Serial No. 536,833

4 Claims. (Cl. 261—30)

The object of this invention is to provide an apparatus for making fuel gas by mixing air and fuel oil and gasoline.

Another object of the invention is to provide an apparatus in which a rotary fan is operated for the purpose of drawing oil or a mixture of oil and gasoline from a tank and mixing it with air and blowing the mixture back into the top of the tank into the clearance space above the oil 10 and maintaining a certain pressure therein which causes the mixed gases to flow out through a suitable supply pipe.

These and other objects of the invention will be illustrated in the drawings, described in the 15 specification and pointed out in the claims at the end thereof.

In the drawings:

Figure 1 is a side elevation partly broken away in section showing the apparatus.

Figure 2 is a top plan view of the apparatus shown in Figure 1.

Figure 3 is a modification of the apparatus shown in Figures 1 and 2.

Figure 4 shows a further modification of the apparatus.

In the drawings like reference numerals indicate like parts.

In the drawings reference numeral 1 indicates a tank having a vertical axis, which preferably will be large enough to hold about five gallons of fuel oil or a mixture of fuel oil and gasoline with a suitable air space therein above the oil. The tank is filled to the level indicated. On top of this tank is provided a fan casing or housing 2 in which is mounted a rotary or centrifugal fan or pump 3. The bottom of the fan casing is open and the fan casing incloses a similar opening 13 in the top of the tank 1 so that the fan can blow air or a mixture of air and oil down through this opening into the tank. The fan is mounted on a horizontal shaft 4 and is driven by a motor or pulley, as may be desired. The shaft 4 is packed with a suitable stuffing box to prevent the leaking of air either in or 45 out.

In the side of the fan casing is an intake opening which is located centrally with regard to the axis of the shaft of the fan. Into this opening is threaded a pipe 5, which extends laterally from the fan casing to an elbow and T joint 6. From this joint extends laterally a check valve 7 and downwardly a pipe 8 which pipe passes into the tank 1 and makes a close joint therewith. This pipe extends to the bottom of the tank 1 or almost thereto, and is serrated on the bottom so

that oil can always pass from the tank into the pipe. In the pipe above the level of the oil is an opening 9 for a purpose that will presently appear.

If the liquid is sufficiently volatile, the pipe 60 need not extend down into the liquid, but may terminate above the liquid.

When the apparatus is operated, the fan 3 is rotated and by centrifugal force the air is thrown out under a moderate pressure and with great 65 velocity to the periphery of the fan case and down through the opening into the tank 1. The pressure created and maintained thereby is about equal to eight inches of water. Fresh air is drawn in through the center of the fan case through 70 the pipe 5 and through the check valve 7, and through the pipe 8. The valve 7 is opened far enough to supply the air as fast as the mixture is drawn off and to secure the correct mixture of air and oil and gas. The air that is drawn 75 up through the pipe 8 enters the pipe at the opening 9 which is located above the level of the oil, but this opening is small enough so that more or less oil is drawn up through the pipe along with the air, and this mixture of oil and 80 air is further mixed with air that is drawn in through the valve 7, and all this mixture is drawn into the fan casing and is mixed by the centrifugal action of the fan, and the oil is more or less vaporized so as to form a stable gaseous 85 mixture. The air and oil so mixed is forced out under some pressure through the opening in the bottom of the fan casing into the top of the tank 1 as above described, and this mixture is in turn drawn into the opening 9 and return to the fan 90 casing through the pipe 8, the air and oil being circulated through the system and being thoroughly mixed.

From the top of the tank 1 leads out a pipe 10 controlled by a valve 11 from which leads a supply pipe 12 through which the combustible mixture is conveyed to the burners of a furnace or to any other place where it is to be consumed or applied to any useful purpose.

In Figure 3 I have shown a modified form of 100 the apparatus which is to be used in the outer air; that is, outside of the house, in which reference numeral 2 indicates the fan casing and this casing is covered by a housing 15 which in turn is covered by a lid 16 which has a ventilating hood 105 17 therein. 18 indicates a pair of wires or electrical conductors leading to the motor by which the fan in the casing 2 is operated, otherwise this apparatus is the same as that shown in Figure 1. In both cases a filler pipe 20 is provided which 110

rises from the top of the tank and through which the tank 1 can be filled. This pipe is closed by a cap 21.

As shown in Figure 4, a tank 1 is provided on top of which is provided a fan casing 25, in which a fan is located similar to that shown in Figure 1. Into this fan casing is drawn a mixture of air and oil from the tank below, just the same as is shown in Figure 1. The fan casing, however, does not open into the tank, but discharges into a conduit 26, through which the mixture of air and oil is conveyed to the point where it is to be used. As shown in Figure 4, an air intake pipe 27 is provided which is controlled by a valve 28, and the air supply that is needed in the tank passes in through the pipe 27.

The direction in which the air or mixture flows is indicated in each case by arrows.

It will be understood that the term oil as used in the specification and claims of this patent means any liquid that is combustible in itself or that is capable of producing a gas or vapor that will burn.

I claim:

1. In an apparatus for producing a combustible gas, the combination of an oil tank containing volatile oil and air, an opening in the top of the tank, a fan casing fixed over said opening, a rotary fan in said fan casing adapted to blow air through said opening into the tank from the periphery of the fan, and a pipe connected to said fan casing concentric to the axis of the fan, said pipe extending down into the tank and making a close joint therewith and into the oil in the tank, said pipe having a small opening therein above the liquid level line and an opening below the liquid level line and being adapted to draw both oil and air into the fan casing and mix them on the rotation of the fan and discharge the mixture into the tank.

2. In an apparatus for producing a combustible gas, the combination of an oil tank containing volatile oil and air, an opening in the top of the tank, a fan casing fixed over said opening, a rotary fan in said fan casing adapted to blow air through said opening into the tank from the periphery of the fan, and a pipe connected to said fan casing concentric to the axis of the fan, said pipe extending down into the tank and making a close joint therewith and into the oil in the

tank, said pipe having a small opening therein above the liquid level line and an opening below the liquid level line and being adapted to draw both oil and air into the fan casing and mix them on the rotation of the fan and discharge the mixture into the tank, said pipe having also an opening above the tank adapted to permit the passage of air into said pipe from the outer air.

3. In an apparatus for producing a combustible gas, the combination of an oil tank containing volatile oil and air, an opening in the top of the tank, a fan casing fixed over said opening, a rotary fan in said fan casing adapted to blow air through said opening into the tank from the periphery of the fan, a pipe connected to said fan casing concentric to the axis of the fan, said pipe extending down into the tank and making a close joint therewith and into the oil in the tank, said pipe having a small opening therein above the liquid level line and an opening below the liquid level line and being adapted to draw both oil and air into the fan casing and mix them on the rotation of the fan and discharge the mixture into the tank, said pipe having also an opening above the tank adapted to permit the passage of air into said pipe from the outer air, and a valve in said opening above the tank to regulate the admission of air.

4. In an apparatus for producing a combustible gas, the combination of an oil tank containing volatile oil and air, an opening in the top of the tank, a fan casing fixed over said opening, a rotary fan in said fan casing adapted to blow air through said opening into the tank from the periphery of the fan, and a pipe connected to said fan casing concentric to the axis of the fan, said pipe extending down into the tank and making a close joint therewith and into the oil in the tank, said pipe having a small opening therein above the liquid level line and an opening below the liquid level line and being adapted to draw both oil and air into the fan casing and mix them on the rotation of the fan and discharge the mixture into the tank, said pipe having also an opening above the tank adapted to permit the passage of air into said pipe from the outer air, said tank having an outlet from said tank above the liquid level line for the combustible gas produced therein.
